KNITTING MACHINE

Harold E. Houseman, Edge Moor, Del., assignor
to Standard-Trump Bros. Machine Company,
Wilmington, Del., a corporation of Delaware

Original application March 16, 1931, Serial No.
522,864. Divided and this application Septem-
ber 24, 1931, Serial No. 564,780

19 Claims. (Cl. 66—43)

This invention relates broadly to a knitted fabric and a method and machine for producing the same. More specifically it relates to a stocking embodying the fabric and a method and machine for making the stocking.

This application is a division of my application Serial Number 522,864, filed March 16, 1931 in which the fabric and method are now claimed.

Heretofore it has been found desirable for 10 various reasons to produce stockings of a type said to have a "split foot" in which the instep, being visible when low shoes are worn, is composed of suitable yarn or yarns generally similar to those used for the leg portion of the stocking, 15 while the sole is composed of different yarn, sometimes undyed to cater to certain hygienic ideas, but in general of heavier or stronger character to better withstand wear. Such stockings generally also involve a split fabric above the heel, in which the rear of the leg above the heel 20 is composed of wear resisting yarn where a low shoe would tend to destroy the fabric, this arrangement involving the so-called "high splice".

The machines heretofore used to produce such 25 stockings involve two feeds, generally designated the sole and instep feeds in view of their particular functions, each of the feeds being associated with the usual knitting cams, etc. In such machines the upper leg is knit from a yarn at the main feed, but the lower leg, at the high splice, and the instep are knit from a similar 30 yarn at the instep feed. Desirably, of course, the same appearance should be maintained continuously from the leg into the instep but since 35 two yarn supplies are necessarily used, and color, weight and texture are rarely duplicated to such degree that differences escape notice, there is almost always a noticeable line of demarcation at the place where change from one yarn to the 40 other occurs. Besides this, the change is further made noticeable by any slight variations in sizes of loops occurring because of varying tensions, different adjustments of cams, etc. Obviously, this change of feeds also makes it difficult if not impossible to continue a design from 45 the leg into the instep.

In an application of Wilbur L. Houseman, 50 Serial Number 511,949, filed January 29, 1931, there is disclosed a fabric, more specifically a stocking, and a method and machine for its production which has portions formed by both rotary and reciprocatory knitting in which the same yarn or yarns are continued from one portion into the other without a break; or specifically, in which a design formed by normal and

reverse plating is so continued without interruption.

It is the broad object of the present invention to provide a fabric having rotary and reciprocatory portions involving designs in each formed by selective floating of a yarn or yarns normally appearing in plating relationship.

It is a further object of the invention to provide both a method and machine for effecting this result and overcoming the difficulties inherent in the manipulation of yarns with the production of float designs during reciprocation. Specifically it is the object of the invention to modify the machine of the Wilbur L. Houseman application above referred to for the production of float designs, various features of this machine being retained.

The accomplishment of these and other objects will be apparent from the following description read in conjunction with the accompanying drawings in which:

Fig. 1 is a plan view, partly in section, of a portion of a machine embodying the invention;

Fig. 2 is a plan view of certain details, parts being omitted for clearness;

Fig. 3 is an inside development of the needle cams;

Fig. 4 is a radially exaggerated development of a plan view of the same showing the positions assumed by the cams during reciprocatory formation of patterns;

Fig. 5 is a diagrammatic view of the butt ends of the various types of needles used in the machine;

Fig. 6 is a side elevation of the upper center cam and its associated parts; and

Fig. 7 is an elevation of a stocking embodying features of the invention.

The illustrated machine is of the rotary needle-stationary cam type having independently movable latch needles and involves various details of construction disclosed in the above mentioned Wilbur L. Houseman application and my Patent 1,725,275, dated August 20, 1929 to which reference may be made for such details, only so much being illustrated in the present disclosure as is necessary for an understanding of the invention. The needle cylinder 2 mounts the needles in the usual fashion, these needles, designated generally by the numeral 4 being of various different types hereafter referred to. Broadly speaking, the needles are arranged in a series consisting of two semicircles one of which is composed of long butt needles, and the other of which is composed of short butt needles with the

exception of the two end ones which have intermediate length butts, certain of the needles being further provided with shoulders of different radial extent for the determination of patterns.

5 The needle cylinder is driven through the usual clutch connections for both rotation and oscillation, one of the intermediate driving gears being illustrated at 6 in Fig. 1.

The needles cooperate in the formation of 10 stitches with the usual sinkers moved by suitable cams in the proper wave. The needles take 15 yarn at two feeds in the present machine designated generally as 8 and 10, the former of which will hereafter be called the instep feed and the latter the sole feed in view of their respective 20 most distinctive functions. These feeds are angularly spaced 112.5° apart, the direction of rotation of the needle cylinder during rotary knitting being counterclockwise as viewed in plan.

25 Referring particularly to Figs. 3 and 4 in which the needle cams are illustrated in developed elevation and exaggerated plan respectively, the cams at the instep feed 8 comprise the upper center cam 12, the lower center cam 14, deflector cams 16 and 18, needle depressing cams 20 and 22, stitch cams 24 and 26, fixed cams 32 and 34, and end cams 36 and 38. Similarly the cams at the sole feed comprise the upper center cam 40, the lower center cam 42, stitch cams 44 and 46, end cams 48 and 50, and guard cam 52. A switch cam 54, angularly located as illustrated in Fig. 2 is urged downwardly by a spring 56 and is designed to engage only long butt needles to elevate them when they move in one direction but to yield to permit them to pass when they move in the opposite direction. A main switch cam 58 is also provided, this cam being carried by a shaft journaled and slidable in a suitable bearing and carrying a pin 60 engaging 40 a slot 62 in the bearing so that when urged to lowered position by a spring 63 it will occupy an outer position wherein it engages long butt needles only but when raised by the action of cam 66 on arm 64 it will move inwardly to engage 45 the butts of all the needles. The cam 66 is carried by an arm 67 moved by the main cam disc as illustrated in the application referred to above, this arm also carrying a cam 68 operable when moved inwardly to effect depression of lowering 50 picker 70 to an inoperative position between the levels occupied by the butts of active and inactive needles as they reach its location. It will be noted that the lowering picker is diametrically opposite the feed 10.

55 The usual raising pickers 72 and 74 are associated with the sole feed.

At the instep feed are located a plurality of 60 yarn fingers 76 arranged to carry the yarns required in the knitting operation, certain or all 65 of these fingers having two or more eyes so that each may carry the plurality of yarns to be associated in plating relationship during the formation of designs. Similar yarn fingers 78 are provided at the sole feed. Both sets of fingers may be controlled by the usual devices to be selectively moved into or out of operation.

In the present machine, the upper center cam 12, instead of being fixed, as is usual, is carried by a slide 77 mounted for radial movements 70 and normally urged inwardly by a suitable spring. This slide at its inner end is provided with a bevel 79 engageable by a plunger 80 which, when engaged by a suitable cam on the main cam disc, moves upwardly forcing the slide outwardly 75 against the tension of the spring.

Slide 82 carries cams 16 and 24 and slide 84 carries similar cams 18 and 26, these slides being urged radially inwardly by springs 90 and 92 to positions wherein adjustable stop screws 86 and 88 therein engage upwardly extending ears 94 and 96 of rocking lever 98, pivoted as indicated at 100 and arranged to be rocked to move the slides simultaneously outwardly by the engagement therewith of the upper end of a plunger 102 movable upwardly by suitable cams on the 10 main cam disc.

The ear 94 is provided with an adjustable stop screw 104 engageable by the end of a lever 106 urged in a clockwise direction by a spring 108, this lever having pivoted thereto arms 112 backed by 15 adjustable stop screws 110 and having beveled ends engageable selectively by stacked levers 114 cooperating with levers 116 carried by the arm 118 which is oscillated by the eccentric groove 124 formed in the gear 6. A lever 122 pivoted to 20 the frame carries members 120 engaging the levers 116, this lever 122 being selectively moved to various positions by engagement by lugs of 25 various heights on the pattern chain 128 trained over the sprocket wheel 126 to which intermittent movements are imparted by the usual pawl carried by the arm 118. The selective mechanism just indicated is not described in full since details thereof are identical with those fully described in my prior Patent 1,725,275 mentioned 30 above. So far as the present invention is concerned it is merely necessary to point out that radial movements of greater or less extent are imparted simultaneously to the slides 82 and 84 through the action of the pattern chain, these 35 movements being effective to produce patterning as will be hereinafter pointed out. Movements imparted by the plunger 102 are independent of those imparted by the pattern chain and are not 40 for patterning purposes.

The mechanism controlling the pattern chain to insure the proper beginning of the pattern producing cycle of operation at the initiation of the knitting of each stocking is fully described in my Patent #1,805,697 dated May 19, 1931, and is 45 merely indicated herein.

Slides 130 and 132 carry the cams 44 and 46, these slides being yieldingly urged inwardly by springs 134 and 136, against the tension of which they are independently movable at proper times 50 by the usual connections actuated by cams on the main cam disc. The various types of needles used in the machine are illustrated in Fig. 5 and comprise long, intermediate and short butt needles shown in rows L, I and S respectively, each 55 of these types including needles having shoulders of various lengths illustrated in columns A, B, and C and needles without shoulders illustrated in column D. As already outlined, there are in the needles circle two intermediate butt needles, located diametrically opposite each other, there being short butt needles on one side of the diameter so defined and long butt needles on the other side. All of these needles are formed either without shoulders or with shoulders of various lengths 60 as illustrated in Fig. 5. While there are four possible intermediate butt needles illustrated, it 65 will be understood that at any time only two are used, the shoulder arrangements thereof being determined by their location in the make-up of a pattern. While three lengths of shoulders are illustrated, either more or less may be provided.

The operation of the machine will be rendered clearer by a preliminary consideration of the stocking to be produced thereby, this stocking, in 75

a preferred form being illustrated in Fig. 7. This stocking comprises a ribbed top *a*, produced as usual on a rib machine and transferred to the needles of the plain fabric machine, an extended top *b*, which may be omitted, consisting of several circularly knit courses, the leg *c* circularly knitted and in the present instance composed of fancy fabric produced by selective plating and floating, this fabric extending continuously into the instep and the upper part of the foot as indicated at *e* and *h*, the high splice *d*, the heel *f*, the split sole *g*, the advanced toe *i*, which may be omitted if desired, consisting of several circularly knit courses, the toe *k*, and the loopers rounds *l*. The parts knitted at the sole feed, particularly the high splice, may be formed of a plurality of yarns in plated relationship.

The radially exaggerated development of Fig. 4 will make clear the positions of the stationary cams and the ranges of movements of the movable cams. In this figure the lines *L*, *I*, *S*, *A*, *B*, *C* and *D* indicate respectively the outward extents of the butts and the shoulders and the face of the needle cylinder. The fixed cams *20*, *22*, *32*, *40* and *52* extend inwardly to a position between the lines *S* and *A* so that they are at all times in position to engage all of the needle butts but clear all the shoulders. The lower fixed cams *14*, *36*, *38*, *48* and *50* may extend inwardly to the needle cylinder preferably forming a portion of the bearing therefor. Movable cams *44* and *46* have a range of movement under the action of the cams referred to above between an extreme inner position between the lines *S* and *A* and outer positions in which they clear the butts of all of the needles, that is, outside the line *L*. The movable cam *12* may occupy alternative positions in one of which it extends between the lines *S* and *A* so as to engage all of the needle butts and in the other of which it extends between the lines *I* and *S* so as to engage the long and intermediate butts but escape engagement with the short butts. The cams associated with the slides *82* and *84* move simultaneously under the action of both the plunger *102* and the pattern chain. The extreme outer position of these carries the cams *24* and *26* outwardly of the line *L* so that they escape engagement with all of the butts. The cams *24* and *26* however during operation move between the lines *S* and *D* so that they engage either all of the needle butts and none of the shoulders or else shoulders of various lengths, the pattern chain determining the movements between these limiting positions. The cams *16* and *18* are so located that even when the cams *24* and *26* are in their extreme operating outward positions these upper deflector cams will at all times engage the long butt needles. As clearly illustrated in this figure, the switch cam *54* engages the long butts only. Likewise the switch cam *58* engages the long butts only when it is in lower position. However, when it is in raised position it moves inwardly due to the pin and slot arrangement illustrated in Fig. 2 so that it will lie between the lines *S* and *A* and thus engage the butts of all of the needles but escape engagement with the shoulders.

When the machine is in stationary condition prior to the beginning of a cycle of operation the needles are levelled to receive the rib top. At this time all of the yarn fingers *76* and *78* are raised out of action, and cams *16*, *18*, *24*, *26*, *44* and *46* are fully retracted to disengage all of the needle butts, the retraction of slides *82* and *84* being effected by the rise of plunger *102* under the

action of a cam on the main cam disc, and the retraction of slides *130* and *132* being similarly effected by plunger connections acted upon by cams on the main cam disc. Switch cam *58* is now raised and in inner position so as to be ready to engage all needle butts (but clear all shoulders), and lowering picker *70* occupies its inoperative position intermediate the levels assumed by the butts of raised and lowered needles during operation, cams *66* and *68* occupying, at this time, inner positions. The pickers *72* and *74* ride the butts. The pattern chain is stationary in a position determining the beginning of a patterning cycle.

Following the transfer of a rib top *a* to the needles, the machine is started to knit a few rounds of yarn similar to that in the rib top to form the portion *b* known as the extended top. Upon starting of the machine, the main cam disc is advanced one step. Cams *24*, *26*, *16* and *18* are allowed to move inwardly in the usual fashion, first dropping against the short butts and then subsequently moving on inwardly as the long butt needles pass through, this inward movement being limited by the position of the plunger *102* which is now engaging a cam of less height on the cam disc. These needle cams now occupy positions between lines *S* and *A* in Fig. 4 so that while they engage butts of all lengths they clear all shoulders. It may be now pointed out that the inner ends of stationary cams *20*, *22*, *32* and *34* also occupy the same positions, the same being true of cams *40* and *52*.

The cams *44* and *46* remain retracted although, if desired, the cam *46* may be permitted to move inwardly to a position between lines *S* and *A* so as to engage the butts of all of the needles and impart an upward wave thereto. This operation is similar to that of the corresponding cam illustrated in the application of Wilbur L. Houseman, Serial Number 511,949 referred to above, the object of the wave being to avoid climbing of the loops at the idle sole feed at the time the sinkers are retracted. Due to this action the loops occupy a lower position on the needles and when the needles are again lowered by the top center cam *40* the fabric loops are drawn down against the stitch drawing edges of the sinkers and the nebs are well above the loops as they move in.

The yarn finger *76* which carries extended top yarn is dropped in advance of the first needle to knit which will be the advancing medium butt suture needle. Thereafter knitting takes place on all of the needles at the instep feed to produce the extended top. During this operation the switch cam *58* remains raised so as not to effect the operation. The cam *54* swings up during each revolution to allow long butt needles to pass, the motion of the needles during revolution being from right to left as viewed in Figs. 3 and 4.

After the extended top is completed the main cam disc is advanced another step and rotary knitting of the upper leg starts. As the movement of the cam disc takes place the extended top yarn finger is withdrawn and another finger, or a plurality of fingers carrying yarns suitable for the leg, are dropped into action at the instep feed. If striping is to take place the fingers originally dropped into action may be replaced by others during formation of the leg in the usual manner, for example, by the mechanism illustrated in my Patent Number 1,769,580.

During this period the fingers at the sole feed remain inactive and the switch cam *58* and cams *44* and *46* retain their previous positions. Ac-

cordingly, stitches are formed solely at the instep feed.

Patterning is now commenced, being accomplished in the present instance by selective plating 5 and floating of the plating yarn. From the following description of operation it will be obvious that a very large variety of designs may be readily produced by the proper selection of shoul-dered needles and pattern cam.

10 As the main cam disc advances the pattern chain 128 is put into operation being stepped intermittently by movements of the arm 118. At the same time the plunger 102 rides off its cam so that the cams 24 and 26 are free to move in-15 wardly against the needle cylinder if such move-ment is permitted by the lugs on the pattern chain. As the knitting now takes place the cams 24 and 26 move inwardly and outwardly so as to be at all times in position to engage all of the butts 20 but selectively engage or clear the various size shoulders. The two yarns extending from the fingers 76 occupy different paths so that while both yarns will be engaged by the needles passing through a normal knitting wave, if any of 25 the needles is prematurely depressed, it will engage one of the yarns and escape engagement with the other so that the latter will float, this latter yarn during normal operation appearing on the face of the fabric in plating relationship 30 to the one which is solely knit upon the occur-rence of the premature depression. The opera-tion of the arrangement in this respect is entirely similar to that described in my prior Patent 1,725,275 and accordingly need not be described 35 in greater detail herein.

Following the rotary knitting of the leg, the main cam disc again advances and reciprocatory knitting begins for the formation of the high splice reciprocation taking place through 360°. 40 Since the pattern is to be continued the yarns previously being knit at the instep feed retain their active locations. The finger 78 which car-ries the high splice yarn or yarns is lowered into action. As the cams 24 and 26 must remain ac-tively engaging shoulders so as to produce pat-45 terns, they cannot be withdrawn as in the Wilbur L. Houseman application to clear the short butt needles which now must not knit at the instep feed, and accordingly other means must be used 50 to render the short butt needles inactive at this feed. To this end, the top center cam 12 is with-drawn to clear the short butt needles by the rise 55 of plunger 80 under the action of a suitable cam on the main disc, the position of cam 12 being such that it continues to engage long and intermediate butt needles. Accordingly, the short butt needles ride over both cams 24 and 26 in moving in both directions. The short butt needles are depressed by cams 20 and 22.

60 Cam 44 now moves into action joining cam 46 which is preferably already in action for the rea-sons pointed out above. Switch cam 58 is low-ered by the partial retraction of lever 67 and simultaneously moves outwardly so that it will 65 engage and raise long butt needles but miss short and intermediate butt needles. The movement of lever 67 is, however, partial so that the lowering picker 70 retains its inactive position, the cam 68 being so designed as not to release it upon 70 such partial movement. The pattern chain con-tinues to move without interruption. Because of reciprocatory knitting the usual take up sweeps through which the yarns at both feeds pass are rendered active.

75 Assuming, first, a counterclockwise reciproca-

tion of the needle cylinder, the intermediate butt needle which leads the long butt needles rides up cam 26 and is depressed by center cam 12 and stitch cam 24 taking either one or both yarns at the instep feed. The taking of the yarns depends of course on the type of shoulder the needle car-ries and the position at that time of the cam 24. It then rides up cam 36, passes switch cam 58 by which it is not engaged and follows the short butt needles up over cam 46 and below cams 40 and 44 taking the high splice yarn at the sole feed and thereby forming a suture between the yarns at the two feeds. The long butt needles follow this suture needle through the cams at the in-step feed and also take one or both yarns at that place. However, the long butts do engage the switch cam 58 and are raised thereby so that they ride above the cams at the sole feed. The long butt needles are brought down into action at the instep feed by the cams 16 and 18.

20 The intermediate butt needle which follows the long butt needles and precedes the short butt needles starts from a position adjacent switch cam 58 and rides up the end of cam 46 until it engages the picker 74 by which it is raised where-25 upon it follows the long butt needles through the cams at the instep feed taking one or more yarns there and finally reaching a position adjacent the switch cam 58 without being raised thereby. The short butt needles following this interme-30 diate butt needle ride over cam 46, beneath the picker 74, are moved downwardly by cams 40 and 44 to take the high splice yarn, pass switch cam 54 without engagement, ride upwardly over cam 26 pass cam 12 without engagement there-35 with, pass above cam 24, and are then depressed by cam 20. In view of the fact that they are not lowered by the cam 24 they do not take any yarn at the instep feed.

40 In a counterclockwise reciprocation a reverse series of events occur. In this case the switch cam 54 takes the place of switch cam 58 and likewise picker 72 lifts the medium butt needle leading the short butt needles.

45 From the above it will be seen that the yarns at the instep feed are selectively knitted by the long butt needles and both of the medium butt needles on each reciprocation with the formation of either plating or floating in accordance with the pattern determined by their shoulders and 50 the pattern chain. The high splice yarn at the sole feed is knitted by the short butt needles and that medium butt needle which leads the long butt needles in that stroke. It is to be observed that this alternate suture operation of the me-55 dium butt needles is desirable since it forms a substantial but non-bulky seam by the avoidance of excessive yarns in the loops thereof. Since the patterning occurs at the instep feed there is no break at the change from rotation to recipro-60 cation.

65 When the knitting at the heel is to begin the main cam disc is again given an intermittent movement and the parts operate to produce the heel in substantially the conventional manner. At this time in order to prevent interruption of the pattern, the pattern chain is stopped in the usual manner by the action of a suitable cam. Cams 16, 18, 24 and 26 are fully withdrawn and yarn finger or fingers 76 previously active are raised, 70 this raising being at a point which will cause the yarn or yarns to knit last on the medium butt which is trailing behind the long butt needles when the cylinder is traveling in a counterclock-wise direction. These yarns may be clamped and 75

cut but are preferably allowed to float from this needle to the raised yarn finger. Cams 44 and 46 remain in action since the heel is to be knit at the sole feed. The cam 68 remains in position 5 to retain the lowering picker 70 inactive.

The change to the heel yarn having been made at the sole feed the narrowing proceeds in the usual manner, the raising pickers 72 and 74 being operative upon the medium and short 10 butt needles while the long butt needles are raised out of action. When narrowing has been completed the cam disc is again stepped around. The only effect of this is to cause lever 67 to rock further outwardly and permit the lowering picker 70 to rise and become operative in the usual manner to lower the needles two at a time while the pickers 72 and 74 continue to raise them one at a time.

When the heel is completed the disc again 20 advances, restoring all of the elements to the position occupied during the knitting of the high splice, the main yarn or yarns being reintroduced so that the suture needle which last knit again resumes knitting while the cylinder travels in a 25 counterclockwise direction. A suitable sole yarn replaces the heel yarn, the movements of the pattern chain continuing from the stopping position. Since the operation is the same as that above described during the formation of the high 30 splice it need not be again repeated.

When the sole is completed the cam disc again advances. All fingers 76 are raised out of action so that withdrawal takes place on the medium butt suture needle following the long butt 35 needles while the cylinder is traveling in a counterclockwise direction, while the finger 78 which carries the heel yarn is lowered into action to replace the sole yarn finger. Cams 16, 18, 24 and 26 are withdrawn. Switch cam 58 is raised. 40 The needle cylinder rotates. Accordingly, all of the needles knit at the sole feed to form the advanced toe i.

The pattern chain now continues to advance until it is arrested, as fully described in my Patent 45 No. 1,805,697. Stopping of the chain will occur at some time during the finishing of the stocking. The chain thus becomes ready to properly start the pattern in a subsequent stocking.

After the formation of the several courses forming the advanced toe the disc again moves bringing the parts into position to perform the narrowing and then the widening for the toe, the motion of the needle cylinder again becoming reciprocatory. The operations in both narrowing 55 and widening resemble those occurring in the formation of the heel and are not therefore repeated.

Following the completion of the widening operation, rotary knitting is resumed, the parts being in the same positions as in the formation of the advanced toe. The several courses thus formed constitute the loopers rounds. It may be noted in this connection that the same yarn is generally used for the heel, advanced toe, toe, 60 and loopers rounds.

After the loopers rounds are completed the yarn is withdrawn so that the loops are pressed off the needles. The cams are then withdrawn to effect levelling and the machine stops. The 70 cycle is thus completed and a new rib-top may be transferred to the machine.

During the above cycle of operation various different yarns have been inserted at both feeds. At the instep feed, for example, there is first inserted the extended top yarn which is of com-

paratively light weight. Similar changes take place at the sole feed, the high splice and sole yarns being generally lighter than the yarn or yarns constituting the heel, toe, etc. Accordingly, in order to produce proper results it is desirable that various cam adjustments be provided. Such adjustments may preferably take the form of those illustrated in the application of Wilbur L. Houseman referred to above to which reference may be made for details.

It will be clear that numerous changes may be made in details of construction and also by the replacement of certain mechanism by non-equivalent but analogous mechanism without departing from the spirit of the invention.

In the following claims for simplicity of expression the term "instep" has been used to apply to the entire front and top split portion of a stocking. That is, it refers broadly to such portions of a stocking as are designated at either 20 c or h, or both, in Fig. 7. Also, where reference is made to a "common" or "same" yarn it will be understood that portions of yarn from the same source are indicated.

What I claim and desire to protect by Letters 25 Patent is:

1. A knitting machine including a circular series of needles, two feeds, elements cooperating with the needles at the feeds to form stitches, means for imparting relative reciprocatory movements to the needles and feeds, and means for effecting manipulation of yarns at at least one of the feeds during reciprocation to produce designs by selective plating and floating, said last means including devices for prematurely selectively depressing needles during movements in both directions relatively to yarns fed from stationary guiding means, the depressed needles failing to engage the same yarn in both movements.

2. A knitting machine including a circular series of needles, two feeds, elements cooperating with the needles at the feeds to form stitches, means for imparting relative reciprocatory movements to the needles and feeds, and means for effecting manipulation of yarns at at least one of the feeds during reciprocation to produce designs by selective plating and floating, said last means including devices for selectively manipulating needles to move them relatively to 45 yarns fed from stationary guiding means to cause them to fail to engage the same yarn during movements in both directions.

3. A knitting machine including a circular series of needles, elements cooperating with the needles in the formation of stitches, means for presenting yarns to the needles at spaced feeds, cams associated with the feeds for actuating the needles and elements during relative rotary or reciprocatory movements, driving means for effecting such rotary or reciprocatory movements, controlling devices for effecting, first, rotary movements while only one feed is active to produce one portion of fabric, and, secondly, reciprocatory movements while both feeds are active 55 to produce a split portion of fabric having two parts, and means for effecting manipulation of yarns at that feed which is active during rotation to produce patterns by plating and floating during both rotary and reciprocatory knitting, said last means including a plurality of devices 60 one of which is operable to selectively manipulate needles during movement in one direction to cause them to move relatively to yarns fed from stationary guiding means to fail to engage one 65

70 said last means including a plurality of devices one of which is operable to selectively manipulate needles during movement in one direction to cause them to move relatively to yarns fed from stationary guiding means to fail to engage one 75

yarn and the other of which is operable to selectively manipulate needles during movement in the opposite direction to cause them to move to fail to engage the same yarn, and pattern mechanism controlling said devices simultaneously whereby a pattern may extend uninterruptedly from a rotary into a reciprocatory knit portion of fabric.

4. A knitting machine including a circular series of needles, elements cooperating with the needles in the formation of stitches, means for presenting yarns to the needles at spaced feeds, cams associated with the feeds for actuating the needles and elements during relative rotary or reciprocatory movements, driving means for effecting such rotary or reciprocatory movements, controlling devices for effecting, first, rotary movements while only one feed is active to produce one portion of fabric, and, secondly, reciprocatory movements while both feeds are active to produce a split portion of fabric having two parts, and means for effecting manipulation of yarns at that feed which is active during rotation to produce patterns by plating and floating during both rotary and reciprocatory knitting, said last means including a plurality of devices one of which is operable to selectively prematurely depress needles relatively to yarns fed from stationary guiding means during movement in one direction to cause them to fail to engage one yarn and the other of which is operable to selectively prematurely depress needles during movement in the opposite direction to cause them to fail to engage the same yarn, and pattern mechanism controlling said devices simultaneously whereby a pattern may extend uninterruptedly from a rotary into a reciprocatory knit portion of fabric.

5. A knitting machine including a circular series of needles including sets of long and short butt needles, needles of both sets being provided with shoulders adjacent the butts and extending outwardly to a less extent than the short butts, two feeds, elements cooperating with the needles at the feeds to form stitches, means for imparting relative reciprocatory movements to the needles and feeds, and means for effecting manipulation of yarns at at least one of the feeds during reciprocation to produce designs by selective plating and floating, said last means including cams for prematurely depressing long butt needles by engagement with shoulders thereof during movements in both directions, the depressed needles failing to engage the same yarn in both movements, and means preventing the depression of short butt needles by said cams during such movements.

6. A knitting machine including a circular series of needles including sets of long and short butt needles, needles of both sets being provided with shoulders adjacent the butts and extending outwardly to a less extent than the short butts, two feeds, elements cooperating with the needles at the feeds to form stitches, means for imparting relative reciprocatory movements to the needles and feeds, and means for effecting manipulation of yarns at at least one of the feeds during reciprocation to produce designs by selective plating and floating, said last means including cams for prematurely depressing long butt needles by engagement with shoulders thereof during movements in both directions, the depressed needles failing to engage the same yarn in both movements, and means preventing the depression of short butt needles by said cams during such movements.

ments, said last means including a retractile center cam adapted, in the operation referred to, to engage long butt needles but not short butt needles.

7. A knitting machine including a circular series of needles including sets of long and short butt needles, needles of both sets being provided with shoulders adjacent the butts and extending outwardly to a less extent than the short butts, two feeds, elements cooperating with the needles at the feeds to form stitches, means for imparting relative rotary and reciprocatory movements to the needles and feeds, and means for effecting manipulation of yarns at at least one of the feeds during both rotation and reciprocation to produce designs by selective plating and floating, said last means including a pair of cams, one of which prematurely depresses both long and short butt needles during rotation by engagement with shoulders thereof, and both of which prematurely depress only long butt needles by engagement with shoulders thereof during reciprocation, whereby in both cases the prematurely depressed needles fail to engage a yarn.

8. A knitting machine including a circular series of needles including sets of long and short butt needles, needles of both sets being provided with shoulders adjacent the butts and extending outwardly to a less extent than the short butts, two feeds, elements cooperating with the needles at the feeds to form stitches, means for imparting relative rotary and reciprocatory movements to the needles and feeds, and means for effecting manipulation of yarns at at least one of the feeds during both rotation and reciprocation to produce designs by selective plating and floating, said last means including a pair of cams, one of which prematurely depresses both long and short butt needles during rotation by engagement with shoulders thereof, and both of which prematurely depress only long butt needles by engagement with shoulders thereof during reciprocation, whereby in both cases the prematurely depressed needles fail to engage a yarn, and means preventing the depression of short butt needles by said cams during reciprocation.

9. A knitting machine including a circular series of needles including sets of long and short butt needles, needles of both sets being provided with shoulders adjacent the butts and extending outwardly to a less extent than the short butts, two feeds, elements cooperating with the needles at the feeds to form stitches, means for imparting relative rotary and reciprocatory movements to the needles and feeds, and means for effecting manipulation of yarns at at least one of the feeds during both rotation and reciprocation to produce designs by selective plating and floating, said last means including a pair of cams, one of which prematurely depresses both long and short butt needles during rotation by engagement with shoulders thereof, and both of which prematurely depress only long butt needles by engagement with shoulders thereof during reciprocation, whereby in both cases the prematurely depressed needles fail to engage a yarn, and means preventing the depression of short butt needles by said cams during reciprocation, said last means including a retractile center cam adapted, during reciprocation, to engage long butt needles but not short butt needles.

10. A knitting machine including a circular series of needles including sets of long and short butt needles, needles of both sets being provided with shoulders adjacent the butts and extending

- outwardly to a less extent than the short butts, two feeds, elements cooperating with the needles at the feeds to form stitches, means for imparting relative reciprocatory movements to the 5 needles and feeds, and means for effecting manipulation of yarns at at least one of the feeds during reciprocation to produce designs by selective plating and floating, said last means including cams for prematurely depressing long butt 10 needles by engagement with shoulders thereof during movements in both directions, the depressed needles failing to engage the same yarn in both movements, and means preventing the depression of short butt needles by said cams during 15 such movements, and pattern mechanism for simultaneously controlling inward and outward movements of said cams whereby they selectively engage shoulders of different lengths.
11. A knitting machine including a circular 20 series of needles including sets of long and short butt needles, needles of both sets being provided with shoulders adjacent the butts and extending outwardly to a less extent than the short butts, two feeds, elements cooperating with the needles 25 at the feeds to form stitches, means for imparting relative rotary and reciprocatory movements to the needles and feeds, and means for effecting manipulation of yarns at at least one of the feeds during both rotation and reciprocation to produce 30 designs by selective plating and floating, said last means including a pair of cams, one of which prematurely depresses both long and short butt needles during rotation by engagement with shoulders thereof, and both of which prematurely 35 depress only long butt needles by engagement with shoulders thereof during reciprocation, whereby in both cases the prematurely depressed needles fail to engage a yarn, and pattern mechanism for simultaneously controlling inward and 40 outward movements of said cam whereby they selectively engage shoulders of different lengths.
12. A knitting machine including a circular 45 series of needles including sets of long and short butt needles, needles of both sets being provided with shoulders adjacent the butts and extending outwardly to a less extent than the short butts, two feeds, elements cooperating with the needles at the feeds to form stitches, means for imparting relative reciprocatory movements to the needles 50 and feeds, and means for effecting manipulation of yarns at at least one of the feeds during reciprocation to produce designs by selective plating and floating, said last means including cams for prematurely depressing long butt needles by engagement with shoulders thereof during movements in both directions, the depressed needles failing to engage the same yarn in both movements, and means preventing the depression of short butt needles by said cams during such 55 movements, said cams serving also to draw down long butt needles by engagement with butts thereof to form plated stitches.
13. A knitting machine including a circular 60 series of needles including sets of long and short butt needles, needles of both sets being provided with shoulders adjacent the butts and extending outwardly to a less extent than the short butts, two feeds, elements cooperating with the needles at the feeds to form stitches, means for imparting relative rotary and reciprocatory movements to the needles and feeds, and means for effecting manipulation of yarns at at least one of the feeds during both rotation and reciprocation to produce designs by selective plating and floating, said last means including a pair of cams, one of 65
- which prematurely depresses both long and short butt needles during rotation by engagement with shoulders thereof, and both of which prematurely depress only long butt needles by engagement with shoulders thereof during reciprocation, whereby in both cases the prematurely depressed needles fail to engage a yarn, said cams serving also to draw down long butt needles by engagement with butts thereof to form plated stitches. 70
14. A knitting machine including a circular 75 series of needles, elements cooperating with the needles in the formation of stitches, means for presenting yarns to the needles at spaced feeds, cams associated with the feeds for actuating the needles and elements during relative rotary or reciprocatory movements, driving means for effecting such rotary or reciprocatory movements, controlling devices for effecting, first, rotary movements while only one feed is active to produce one portion of fabric, and, secondly, reciprocatory movements while both feeds are active to produce a split portion of fabric having two parts, a plurality of yarns being presented to the needles at one of said feeds during reciprocation, and means individual to the needles effective during reciprocation to produce selective relative positioning of the needles and yarns at a point where the needles move to take yarns at the last named feed to produce patterns by plating and floating during reciprocatory knitting. 80
15. A knitting machine including a circular 85 series of needles, elements cooperating with the needles in the formation of stitches, means for presenting yarns to the needles at spaced feeds, cams associated with the feeds for actuating the needles and elements during relative rotary or reciprocatory movements, driving means for effecting such rotary or reciprocatory movements, controlling devices for effecting, first, rotary movements while only one feed is active to produce one portion of fabric, and, secondly, reciprocatory movements while both feeds are active to produce a split portion of fabric having two parts, a plurality of yarns being presented to the needles during both rotation and reciprocation at that feed which is active during rotation, and means individual to the needles effective during both rotation and reciprocation to produce selective relative positioning of the needles and yarns at a point where the needles move to take yarns at the last named feed to produce patterns by plating and floating during both rotary and reciprocatory knitting. 90
16. A knitting machine including a circular 95 series of needles, two feeds, elements cooperating with the needles at the feeds to form stitches, means for imparting relative reciprocatory movements to the needles and feeds, a plurality of yarns being presented to the needles at one of said feeds during reciprocation, and means individual to the needles effective during reciprocation to produce selective relative positioning of the needles and yarns at a point where the needles move to take yarns at the last named feed to produce patterns by plating and floating during reciprocatory knitting. 100
17. A knitting machine including a circular 105 series of needles, two feeds, elements cooperating with the needles at the feeds to form stitches, means for imparting relative reciprocatory movements to the needles and feeds, a plurality of yarns being presented to the needles at one of said feeds during reciprocation in both directions, and means individual to the needles effective during reciprocation to produce selec- 110

tive relative positioning of the needles and yarns at a point where the needles move to take yarns at the last named feed to produce patterns by plating and floating during reciprocatory knitting in both directions.

18. A knitting machine including a circular series of needles, a feed, elements cooperating with the needles at the feed to form stitches, means for imparting relative reciprocatory movements to the needles and feed, and means individual to the needles effective during reciprocation to produce selective relative positioning of the needles and yarns at a point where the needles move to take yarns at said feed to pro-

duce patterns by plating and floating during reciprocatory knitting.

19. A knitting machine including a circular series of needles, a feed, elements cooperating with the needles at the feed to form stitches, means for imparting relative reciprocatory movements to the needles and feed, and means individual to the needles effective during reciprocation in both directions to produce selective relative positioning of the needles and yarns at a point where the needles move to take yarns at said feed to produce patterns by plating and floating during reciprocatory knitting in both directions.

HAROLD E. HOUSEMAN. 15
